LOOSE-LEAF BINDER

Eulie G. Dortch, Nashville, Tenn.

Application December 27, 1938, Serial No. 247,907

2 Claims. (Cl. 129—18)

This invention relates to loose-leaf binders and has for an object to provide a loose-leaf binder which will be devoid of posts.

A further object is to provide a loose-leaf binder having a pair of lever operated hooks mounted on the back of the binder and adapted to hook into recesses in the edges of the leaves to detachably secure the leaves in the binder.

A further object is to provide a device of this character which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification,

Figure 1 is a rear elevation of a loose-leaf binder with a portion of the back broken away to expose the lever operated leaf engaging hooks.

Figure 2 is a fragmentary side elevation of the binder shown in Figure 1 with portions broken away.

Figure 3 is a detail perspective view of one of the lever operated hooks.

Figure 4 is a fragmentary perspective view of the binder leaves showing the notches therein for receiving the hooks.

Figure 5 is a fragmentary cross sectional view taken on the line 5—5 of Figure 2 showing the channel member for receiving the rear edges of the leaves.

Referring now to the drawing in which like characters of reference designate similar parts in the various views, the loose-leaf binder comprises a flat sheet metal back 10 having the edges rolled back to form hinge eyes 11 to receive hinge pintles 12 which are passed through hinge eyes 13 carried by the stiff side covers 14 of the book, there being slots 15 in the hinge eyes of the back, as shown in Figure 2, to receive the hinge eyes of the side covers.

A channel member 16 is riveted or otherwise secured to the sheet metal back 10 to receive the rear edges 17 of the loose leaves 18. The channel member holds the leaves accurately tacked to locate transverse grooves 19 of the leaves, shown in Figure 4, in position to receive the locking hooks later described. A removably

mounted back member 20, of concave contour, is provided with a plurality of cross members 21 which terminate in resilient hooks 22 that embrace the hinge eyes 13 of the side walls 14, as shown in Figure 5, to detachably mount the member in place. This back member forms a housing for the locking hooks about to be described.

There are two locking hooks 23, preferably formed of sheet metal, one of which is shown in Figure 3. The flat shanks of these hooks extend oppositely to each other along the sheet metal back 10 and the free hooked ends 24 are adapted to be received in the grooves 19 of the leaves 18 to hold the leaves clamped in the channel member at the upper and lower edges of the leaves. The opposed ends of the locking hooks are connected to respective ends of a short lever 25 which is pivoted intermediate its ends as shown at 26 in Figure 1 upon the metal back 10 at about the center thereof. One of the hooks is equipped with a handle 27 which is secured at one end as shown at 28 to the hook and at the free end is bent laterally to provide a grip 29 through the medium of which the handle may be pulled outwardly or shoved inwardly to correspondingly move the hooked ends 24 of the locking hooks out of or into engagement with the grooves 19 of the leaves 18.

In operation when the hooked ends 24 of the locking hooks are engaged in the grooves 19 in the ends of the leaves 18, the leaves are held securely in the channel member 16. When the grip 29 of the handle 27 is pulled outwardly the respective locking hook 23 is moved outwardly and rocks the lever 25 on its pivot to simultaneously move outwardly the companion locking lever 23 and disengage the hooked ends of both locking hooks from the grooves in the leaves.

From the above description it is thought that the construction and operation of the invention will be fully understood without further explanation.

What is claimed is:

1. A loose-leaf binder comprising a back, covers hinged to the back, a channel member extending longitudinally of the back, leaves confined at the rear portions thereof in the channel member and having a line of transverse grooves in the top and bottom edges, hook members slidably mounted on the back and projecting from respective opposite ends of the back, a lever pivoted intermediate its ends on the back and pivotally connected to opposed ends of the hook members, and means on one of the hook members for mov-

engaging the hook members into and out of engagement with said grooves.

2. A loose-leaf binder comprising a back plate having rolled edges providing hinge eyes, side covers having hinge eyes interleaved between the hinge eyes of the back plate, pintles engaged through said interleaved hinge eyes, a removable back element for the binder having resilient hooks projecting from the longitudinal edges engageable over said hinge eyes to removably hold the

10

back element in place, a channel member secured to said back plate, leaves having the rear portions removably fitted in said channel member and having transversely aligned grooves on the top and on the bottom edges, and hook members 5 slidably mounted on the back and housed by said removable back member, said hook members being adapted to be engaged in and disengaged from said grooves.
